UNITED STATES PATENT OFFICE

EDWARD H. LEHMAN, OF CHICAGO, ILLINOIS, ASSIGNOR TO W. H. MINER, INC., OF CHICAGO, ILLINOIS, A CORPORATION OF DELAWARE

CAR CONSTRUCTION

Application filed June 18, 1928. Serial No. 286,356.

This invention relates to improvements in car construction.

In railway cars it is highly desirable to connect the body and truck bolsters so that they will not separate in service in the event of collision, thereby preventing telescoping of the cars. Locking pins of various types have been heretofore employed for this purpose, which are locked so as to prevent accidental removal of the same. It has been found difficult to provide an efficient locking arrangement without seriously complicating the locking pin structure and the locking means.

It is one object of my invention to provide a simple, efficient and reliable locking arrangement for center pins for connecting body and truck bolsters of railway cars, wherein the pin may be readily applied and securely locked to prevent accidental removal.

A further object of the invention is to provide a bolster connection for railway cars, including a solid locking pin headed at one end and held against removal by a locking key extending through the opposite end of the pin.

A still further object of the invention is to provide a bolster locking center pin so designed as to readily permit separation of the body and truck bolsters without the necessity of obtaining access to either the upper side of the body bolster or the under side of the truck bolster, after the pin has once been applied, by merely withdrawing the locking means associated therewith, the locking means being readily accessible at one side of the bolster.

Other and further objects of the invention will more clearly appear from the description and claims hereinafter following.

In the drawing, forming a part of this specification, Figure 1 is a top plan view of a body bolster of a railway car, illustrating my improvements in connection therewith, the top plate of the body bolster being omitted to more clearly illustrate the invention. Figure 2 is a vertical, transverse, sectional view, corresponding substantially to the line 2-2 of Figure 1. And Figure 3

is an elevational view of the center pin forming a part of my improved body and truck bolster connecting means.

In said drawings, 10 indicates the body bolster and 11 a portion of the truck bolster of a railway car. The types of bolsters illustrated are commonly used in railway equipment and illustrate one application of my improvements, it being evident that the improved locking means is capable of use in connection with any of the well known types of bolsters in use.

The body bolster 10 is made up of sections, which are secured to the spaced center or draft sills 12 of the railway car underframe structure. As shown, top and bottom plates 13 are employed which are disposed above and below the draft sills, the plates being connected by the usual spaced diaphragm members 14 at opposite sides of the center sills. Between the center sills 12, the usual bolster filler casting 15 is employed. The parts of the bolster structure may be secured together in any suitable manner and are herein shown as connected by rivets. Between the bottom plate 13 of the bolster and the filler casting is interposed a filler plate 16, which also abuts the bottom flanges of the draft sills 12.

The body bolster is provided with the usual center bearing member 17, which has an annular projecting portion cooperating with the center bearing member 18 of the truck bolster. As shown, the center bearing member 18 of the truck bolster is provided with an annular seat which receives the projection of the bearing member 17 of the body bolster.

The portion of the truck bolster member, which is indicated by 11, is the section of the bolster casting which carries the center bearing plate or member. As shown, the casting 11 is provided with a pocket 19 at the upper side thereof, which receives the center bearing member 18, a filler plate 20 being interposed between the bottom wall of the pocket and the center bearing member.

The body and truck bolsters are provided with aligned center pin-receiving openings 21-21 to accommodate a cylindrical center

pin. The opening 21 of the casting 11 is enlarged at the lower end, as indicated at 22, to provide a pocket or seat. The opening 21 of the casting 15 of the body bolster is also enlarged at the upper end to provide a pocket 23. As shown, the pocket 23 is relatively deep and has an annular side wall 24.

In carrying out my invention, I provide a solid center pin A, a locking key B, and spacing shims or washers C.

The locking pin A has a cylindrical shank portion and is provided with a head 25 at the bottom end. At the free end, the shank of the pin A is provided with a transverse opening 26, which is of rectangular section, as shown. When the pin A is in position, the head 25 thereof is disposed within the pocket 22 of the truck bolster casting 11, with the shank extending through the aligned openings 21—21 of the truck and body bolsters. In this connection, it is pointed out that the bearing members 17 and 18 of the body and truck bolsters are also provided with openings to accommodate the shank of the center pin A.

The center pin A is locked against removal from the body and truck bolsters by the key B, which is in the form of a heavy bar of rectangular cross section. As shown, when the parts are assembled, the key B extends through the opening 26 at the free end of the center pin A, the side wall 24 of the pocket 23 being vertically slotted, as indicated at 27, to accommodate the key. The key is of such a length as to extend through the center sill 12 at the right-hand side of Figure 2, the center sill being also provided with an opening 28 to accommodate the key. The corresponding side wall of the casting 15 is also slotted to accommodate the key B. As clearly shown in Figure 2, the slots provided in the casting 15 and the opening 28 provided in the center sill 12 are of such a height as to permit a certain amount of vertical displacement of the key B.

The free end of the key B projects an appreciable distance outwardly of the sill 12, and in order to maintain the key engaged within the opening 26 of the pin A anchoring means is provided on the sill 12. The anchoring means comprises a pair of angle plates 29—29 secured to the outer side of the sill 12, the angle plates presenting spaced flanges disposed on opposite sides of the key B. The spaced flanges are vertically slotted, as indicated at 30, to accommodate a locking bolt 31 for limited vertical movement. The locking bolt 31 extends through the slots 30 of the angle plates and an opening 32 provided at the end of the key B.

In order to prevent excessive vertical displacement of the pin A, with respect to the bolsters, a plurality of shims C, in the form of washer-like rings, are interposed between

the bottom wall of the pocket 23 and the key B.

As will be evident, my improved center locking pin may be readily connected to the body and truck bolsters of cars of various types, including those having either four- or six-wheel trucks. In the case of four-wheel trucks, the pin may be readily inserted from the bottom of the truck bolster, inasmuch as the axle members of the truck are on opposite sides of the opening which receives the center pin. When the pin is applied to the six-wheel type of truck, wherein the central axle is disposed immediately below the center pin-receiving opening, the center pin is inserted before the parts of the truck have been completely assembled. With the center pin thus placed in position, the body bolster is assembled with the truck bolster and the pin engaged within the opening 21 of the body bolster. After the parts have been thus engaged, the key B is inserted through the opening 28 of the center sill 12 and engaged within the opening 26 at the free end of the center pin, the proper number of shims C having first been placed in position about the shank of the center pin. When the key B has been engaged with the center pin, the pin is locked to the body and truck bolsters, upward movement of the pin with respect to the truck bolster being prevented by the head 25 and downward movement of the pin with respect to the body bolster being prevented by the key B which projects beyond the side walls of the opening 21 in the casting 15. The key is then locked by the bolt 31 and is thus anchored to the center sill 12 in such a manner as to prevent longitudinal displacement of the key, but permitting limited vertical movement of the same to allow for adjustment of the center pin.

When it is desired to separate the body and truck bolsters of the railway car, the anchoring bolt 31 is first removed, and the key is then withdrawn from the opening 26 of the center pin A. As will be evident, the body bolster may then readily be lifted from the truck bolster or the center pin A may be removed by withdrawing the same from the bottom side of the truck bolster.

From the preceding description, taken in connection with the drawings, it will be evident that I overcome the difficulties and disadvantages which are inherent in former types of center locking pins. The arrangement is such that the locking pin may be applied to any well known types of bolsters, and, further, that no special designs of bolsters are required, and the locking center pin and retaining means may also be manufactured at low cost.

While I have herein shown and described what I consider the preferred manner of carrying out my invention, the same is merely illustrative and I contemplate all changes and

modifications which come within the scope of the claims appended hereto.

I claim:

1. In car construction, the combination with body and truck bolsters having aligned center pin-receiving openings, the opening of the truck bolster being enlarged at the bottom end to provide a pocket and said body bolster having a shoulder adjacent the opening thereof; of a headed pin connecting said bolsters, the head of the pin being seated in said pocket and having shouldered engagement with the inner wall of the pocket; a key extending through the free end of the pin and extending through a wall member of the body bolster; and spacing means interposed between the key and the shoulder adjacent the pin-receiving opening of the body bolster.

2. In car construction, the combination with body and truck bolsters having cooperating center bearing portions; of a center pin extending through said bolsters for connecting the same, said pin having shouldered engagement with one of said bolsters to hold the same against removal in one direction, the other bolster having an abutment shoulder; a locking element extending through said last named bolster and the corresponding end of the pin for preventing removal of the center pin in a reverse direction; and removable spacing means between said locking element and the shoulder of the last named bolster to hold the pin in shouldered engagement with said first named bolster.

35 In witness that I claim the foregoing I have hereunto subscribed my name this 15th day of June 1928.

EDWARD H. LEHMAN.
